(57) **CLAIM**

The ornamental design for an adjustable branch separator device, as shown and described.

DESCRIPTION

FIG. 1 is a front perspective view of an adjustable branch separator device, showing my new design;

FIG. 2 is a front elevational view thereof, the rear elevational view being the same as the front elevational view;

FIG. 3 is a left side elevation view thereof; the right side elevation view being a mirror image of the left side elevation view;

FIG. 4 is a top plan view thereof; and,

FIG. 5 is a cross-sectional view taken along 5-5 in FIG. 2. The broken lines showing of the plant is for illustrative purposes only and is not part of the claimed device.

1 Claim, 3 Drawing Sheets
